UNITED STATES PATENT OFFICE.

WILLIAM C. McKEOWN, OF BUFFALO, NEW YORK, ASSIGNOR TO W. A. CASE & SON MFG. CO., OF BUFFALO, NEW YORK, A CORPORATION OF NEW YORK.

DESIGN FOR A RADIATOR.

49,190.

Specification for Design. Patented June 13, 1916.

Application filed April 24, 1916. Serial No. 93,337. Term of patent 14 years.

To all whom it may concern:

Be it known that I, WILLIAM C. McKEOWN, a citizen of the United States, residing at Buffalo, in the county of Erie and State of New York, have invented a new, original, and ornamental Design for Heating-Radiators, of which the following is a specification, reference being had to the accompanying drawing, forming part thereof.

Figure 1 is a perspective view of the radiator showing my new design. Fig. 2 is an end view of the same. Fig. 3 is a plan view.

I claim:

The ornamental design for a radiator as shown.

WILLIAM C. McKEOWN.
